UNITED STATES PATENT OFFICE.

PAUL D. SIDEY AND GLEN L. HARLEY, OF GOLDFIELD, COLORADO.

AUTOMATIC FILTER-SCRAPER SHIFTER.

1,296,865.

Specification of Letters Patent. Patented Mar. 11, 1919.

Application filed February 3, 1917. Serial No. 146,467.

To all whom it may concern:

Be it known that we, PAUL D. SIDEY and GLEN L. HARLEY, citizens of the United States, residing at Goldfield, in the county 5 of Teller and State of Colorado, have invented certain new and useful Automatic Filter-Scraper Shifters, of which the following is a specification.

Our invention relates to an automatic filter 10 scraper shifter, and is designed to overcome the objectionable features of the present filter-press in general use, it being adapted for attachment to the scraper on a continuous discharge filter-press. In present-day presses, the scraper is stationary, and quickly wears out the canvas, and is itself worn into grooves by the wires of the press, which necessitates constant patching, 15 filing, and resultant shut-down of the machine.

Our present invention overcomes these defects by its means for imparting a slow, steady, endwise movement of the scraper back and forth across the press, while requiring no additional power and no mechanical skill to attach or apply it, or to insure its perfect action and operation.

In the accompanying drawings:—

Figure 1 is a view in end elevation;

Fig. 2 is a plan view;

Fig. 3 is a sectional view through the bracket and shifting-lever or arm; and

Fig. 4 is a sectional view through the extension-shaft coupling.

A, represents the side end of the filter-press frame, to which our scraper shifter is attached. The numerals 1 and 2 represent brackets secured to said side end of the filter-press frame by bolt-screws or other 35 means, and 3 is a brace similarly attached and connected to the bracket.

The numeral 4 represents the shifting arm in the form of a bell-crank lever, pivoted at its center to the brackets 1 and 2 and 45 brace 3 by a pin or bolt 5. This arm or lever 4 is preferably actuated by means of the eccentrically placed wrist-pin 6, on the end of the filter-press shaft 7, through the medium of a connecting-rod 8, which is pivotally connected with the outer end of said

arm or lever 4. This connecting-rod may be variously constructed, and preferably is made in two parts, connected by a screw and nut, whereby it may be made adjustable or extensible, according to the requirements 55 and the length of stroke desired to be imparted to the scraper.

The numeral 9 is the extension-shaft to the scraper S, it having sliding connection through the sides of the filter press-frame 60 and it is reciprocated through the rocking motion of the arm or lever 4, actuated by the filter-press-shaft 7 through the extensible connecting rod 8.

The one end of the shifting-arm or lever 65 is connected to the extension-shaft 9 in any approved manner, as for instance through the coupling-sleeve 10, which is held adjustably on the extension-shaft 9 by a set-screw 11. This coupling-sleeve 10 has a mortise 70 12 therein, in which the tenoned end 13 of the shifting arm or lever operates in the form of a ball and socket joint. A coupling-collar 14 is connected with the opposite end of the shaft 9 by set-screws, and affords 75 a means of coupling thereto the scraper-shaft.

While our description has been confined strictly to the illustrated form of our invention, it is obvious that it might take other 80 forms, more or less modified, the essential feature of our invention being a means for actuating the scraper, which hitherto has been stationary, by imparting thereto a slow, steady movement back and forth in contact 85 with the filter-press.

We claim:—

1. The combination with a filter press frame and an extension shaft carrying a scraper and slidably supported in the sides 90 of the filter press frame, of a bell-crank lever detachably connected with said extension shaft, and a connecting rod extending from the bell crank lever to the filter press shaft and reciprocated thereby, whereby to rock the bell crank lever and reciprocate the scraper.

2. The combination with a filter press frame and an extension shaft carrying a scraper and slidably supported in the sides 100

of the filter press frame, of a bell-crank lever detachably connected with said extension shaft, a connecting-rod extending from the bell crank lever to the filter press shaft and reciprocated thereby, whereby to rock the bell crank lever and reciprocate the

scraper, and means for regulating the length of the scraper stroke.

In testimony whereof we affix our signatures.

PAUL D. SIDEY.
GLEN L. HARLEY.

Copies of this patent may be obtained for five cents each, by addressing the "Commissioner of Patents, Washington, D. C."
